UNITED STATES PATENT OFFICE.

PERCY D. CALLAHAN, OF DECATUR, ILLINOIS, ASSIGNOR TO FARIES MANUFACTURING CO., OF DECATUR, ILLINOIS, A CORPORATION OF ILLINOIS.

DESIGN FOR A LIGHTING-FIXTURE.

48,967.

Specification for Design.

Patented May 2, 1916.

Application filed February 7, 1916. Serial No. 76,862. Term of patent 7 years.

To all whom it may concern:

Be it known that I, PERCY D. CALLAHAN, a citizen of the United States, residing at Decatur, in the county of Macon and State of Illinois, have invented a new, original, and ornamental Design for a Lighting-Fixture, of which the following is a specification, reference being had to the accompanying drawing, forming a part thereof.

The figure is a perspective view of a lighting fixture, showing my new design.

I claim:

The ornamental design for a lighting fixture, as shown.

PERCY D. CALLAHAN.
